UNITED STATES PATENT OFFICE.

HENRY C. HINCHCLIFF, OF BROOKLYN, NEW YORK.

PUNCHING AND EYELETING MACHINE.

1,120,939.

Specification of Letters Patent. Patented Dec. 15, 1914.

Application filed February 24, 1912. Serial No. 679,723.

To all whom it may concern:

Be it known that I, HENRY C. HINCHCLIFF, a citizen of the United States, residing at Brooklyn, in the county of Kings and State of New York, have invented new and useful Improvements in Punching and Eyeletting Machines, of which the following is a specification.

My invention relates to the class of machines known as punching and eyeletting machines, by means of which a hole is punched in a piece of material and an eyelet introduced into the hole and set in the material.

The object in general of the invention is to provide an improved punching and eyeletting machine adapted to perform its work, in a minimum number of operations, with a high degree of accuracy and efficiency.

A more particular object of the invention is to provide an improved punching and eyeletting machine which will punch the hole in the material and without withdrawing the punch from the material and shifting the material either longitudinally or transversely set the eyelet in the material within the hole punched therein, thus insuring accurate registration of the eyelet with the hole.

Another particular object of the invention is to provide an improved eyeletting machine comprising means for positively actuating the mechanisms for feeding the eyelet, punching the hole in the material and introducing the eyelet into the hole in the material and setting the eyelet in the material, thus insuring efficiency of operation of said mechanisms.

Other objects of the invention will appear from the following description.

Referring to the drawings Figure 1 is a right side elevation of my improved eyeletting machine; Fig. 2 is a left side elevation of the machine; Fig. 3 is a front elevation of the machine; Fig. 4 is a view illustrating how the eyelet is delivered to the eyelet feed; Figs. 5 and 6 are views illustrating how the eyelet is fed into position to be impaled upon the punch and to be set in the material; Fig. 7 is a view showing the eyelet impaled upon the punch and the punch in the position it assumes when it has punched a hole in the material; Fig. 8 is a view showing the punch, material and eyelet elevated and the anvil brought thereunder to permit the eyelet shank to be pushed

through the hole in the material; Fig. 9 is a view showing the punch, material and eyelet again elevated, after the eyelet shank has been pushed through the hole in the material, and the anvil brought into position to set the eyelet in the material; Fig. 10 is a view showing the operation of setting the eyelet in the material; Fig. 11 is a sectional view of the punch, co-acting die and its supporting parts; Fig. 12 is a sectional view of the set and the slide upon which it is mounted; Fig. 13 is a sectional view illustrating the adjustable connection between the set slide and its operating parts.

Similar characters of reference refer to similar parts of the machine throughout the several views of the drawings.

The operating parts of the machine are mounted upon a frame 1. The frame is provided with a support 2 upon which the material rests when it is punched in the manner hereinafter described. Said support is provided with an opening 3 in which rests the die holder 5. The die holder is recessed at 6 to receive the die 7 which is provided with a punch receiving opening 8. The die holder is provided with a passage 9 with which the punch receiving opening 8 registers and through which the piece of material which is punched out passes from the die. The upper end of the die holder is provided with an inclined flange 10 which engages and rests upon a correspondingly inclined seat 11 at the upper end of the opening 3 in the support. The lower end of the die holder is threaded to receive a nut 12 which engages the under surface of the support 2. The die holder is slit at its upper end at 13 so that said end of the die holder may be compressed to grip the die 7 firmly and hold it in position upon turning the nut 12 and thereby drawing down the inclined flange 10 of the die holder against its seat 11. A punch 14 is adapted to co-act with the die 7 to punch a hole in the material in which the eyelet is adapted to be set. A set 15 is adapted to engage the eyelet and push it into the hole punched in the material and to set the eyelet in the material. The punch and set are respectively mounted upon a punch plunger 16 and a set plunger 17. The upper end of the punch rests in an opening in the punch plunger 16 and is secured to the plunger by a set screw 18. Said punch plunger is slidably mounted in a guide way 19 in the set plunger 17 which is slidably mounted

in a guide 20 on the frame 1. The punch plunger and punch are actuated by a cam 21, in cam disk 22 mounted on shaft 23 journaled in the frame 1, and cam lever 25 fulcrumed at 26 upon the frame 1. Said lever is connected to said plunger by means of a stud 28 and link 29. The stud is mounted on the punch plunger and projects therefrom through slots 17^a and 20^a respectively in the set plunger 17 and guide 20, and is connected at its outer end to one end of the link 29, the other end of which is connected to the cam lever 25. The cam lever 25 is provided with a cam roller 25^a which engages the cam 21. The set 15 is supported on the lower cross member 31 of the set plunger 17, resting in an opening 32 in said member, which opening is inclined at its lower end to form a seat 33 against which rests an inclined flange 34 on the set 15. The upper end of the set is threaded to receive a nut 35 which engages the upper face of the cross member 31 and draws the flange 34 against its seat 33 whereby the set is maintained in position on the plunger. The set 15 is provided with an opening 35 through which the punch 14 extends and reciprocates. The set plunger and set are actuated by a cam 40 in cam disk 22 and cam lever 41 which is fulcrumed at 26 upon the frame 1. The cam lever 41 is provided with a roller 41^a which engages the cam 40. Said lever is connected to the set plunger by means of link 42 and the adjusting union 43. The adjusting union 43 comprises a screw 44 having a flat sided flange 45, connecting element 46 which is connected to link 42, washer 47, wrench 48 and lock nut 49. The respective ends of the screw 44 are threaded in opposite directions and engage corresponding internal threads 50 and 51 respectively in the upper end of set plunger 17 and in the lower end of connecting element 46. The washer 47 rests upon the upper end of the set plunger and supports the wrench 48 which is provided with a flat sided opening 52, in which rests the screw flange 45, the sides of which opening are adapted to engage the sides of said flange, when the wrench is turned, and cause the screw to turn. The lock nut 49 is provided with an internal thread 53 which engages an external thread 54 on the lower end of the connecting element 46, by means of which the nut is screwed against or away from the wrench 48. Upon turning the screw 44 by means of the wrench 48 the set plunger 17 and the connecting element 46 are drawn toward or moved away from each other whereby the set is adjusted to receive its proper movement from the cam lever 41 to set the eyelet securely in the material. The set plunger and set are locked in their adjusted position by turning the lock nut 49 until the wrench 48 is gripped firmly

between the nut and washer 47 so that the sides of the opening 52 in the wrench 48 will engage the sides of the screw flange 45 and prevent the screw turning.

A slideable anvil 60, mounted in a guide 61 in the frame 1, is adapted to slide between the die 7 and the material, after a hole is punched in the material and the material is elevated, in the manner hereinafter described, and is provided with an opening 62 and a die 63 adapted to co-act with the punch and set in introducing the eyelet in the hole in the material and in setting the eyelet in the material, in the manner hereinafter more fully described. The anvil 60 is actuated by a cam 65 in cam disk 66 mounted upon shaft 23 and cam arm 67 fulcrumed at 68 on the frame 1. Said arm is connected to the anvil by link 69. The cam arm 67 is provided with a cam roller 70 for engaging the cam 65 to effect the operation of the anvil through the cam arm by the cam. The material, after a hole is punched therein, is positively lifted off the die 7, to permit the anvil 60 to slide between the material and the die, by means of a lifting arm 72 on cam arm 73 which is fulcrumed at 74 on the frame 1. The cam arm 73 is provided with a cam roller 75 which engages a cam 76 on cam disk 22, whereby the lifting arm is actuated. A spring 77 is connected to the lifting arm 72 and to the frame 1 to insure the downward movements of said arm.

A feed bar 80 provided with a recess 81, for receiving the eyelet, and a spring dog 82, under the tension of spring 83 for engaging and maintaining the eyelet in said recess, is adapted to feed the eyelet into a position where it receives the punch and is engaged by the set to be introduced into the hole in the material and to be set in the material. The feed bar 80 may also be provided with an engaging spring member 85 to engage the eyelet and maintain it in its proper position on the feed bar to insure registration of the eyelet with the punch and set, when the eyelet is fed to the punch and set. A cam 90 may be provided on the frame 1 to be engaged by a lug 91 on the member 85 to raise the member sufficiently to permit the eyelet to pass under the member into the feed bar recess 81 from a chute to be described hereinafter. The feed bar 80 is operatively mounted in the guide 61 and is actuated by cam 95 in cam disk 66 and cam arm 96 fulcrumed at 68. The cam arm 96 is provided with a cam roller 97 which engages the cam 95 and is connected to the feed bar 80 by link 98 whereby the operation of the feed bar is effected by the cam through the cam arm.

The eyelets are delivered upon the feed bar 80 from a magazine 100, through a chute 101. The chute 101 is mounted upon a plate

102 secured to the frame 1. The magazine 100 is loosely mounted upon a shaft 103 journaled in bearing 104 on the plate 102. The magazine is open at one end which end rests 5 against the upper portion of the plate 102. The upper portion of the plate 102 is provided with a recess 105 which registers with the open end of the magazine and communicates with the upper end of the chute 101. The side wall of the magazine is inclined so 10 that the eyelets will roll into the recess 105 in the plate 102. The eyelets are supplied to the magazine through a hopper 106. The shaft 103 is provided with an arm 107 which 15 is connected to cam lever 25 by link 108, whereby said shaft is oscillated by said lever. A brush 110 mounted upon the shaft 103 within the recess 105 is oscillated with the shaft to sweep the eyelets into the upper 20 end of the chute 101. The magazine 100 is locked to the shaft 103, to oscillate therewith to agitate the eyelets by means of a pin 111 on arm 112 which is detachably mounted on the end of said shaft outside of the closed 25 end of the magazine, and holes 100^a in said end of the magazine which are adapted to receive said pin. Said end of the shaft 103 is flattened and fits in a slot 113 in the arm 112 whereby the arm is locked to the shaft 30 so that the arm will oscillate with the shaft. The arm is held on the end of the shaft by means of a pin 114 fitting in the end of the shaft. The magazine 100 is provided with a door 115 and may be manually turned upon 35 disengaging the pin 111 from the shaft 103 in which it rests, into such position that the eyelets may be removed from the magazine, if desirable, through said door, upon opening the door. A spring dog 116 pivoted in 40 the lower end of the chute 101 and under the tension of spring 117 forms the lowermost extremity of the forward side wall of the chute and is normally maintained in parallel alignment with the main section of said wall 45 by its spring 117 so that the eyelets normally will be guided into the recess 81 in the feed bar 80 as they drop through the chute. A pulley 120 mounted on shaft 23 is adapted to be belted to a source of power, (not 50 shown) for the purpose of driving the shaft 23. The pulley 120 may be provided with any well known commercial clutch (not shown) to connect the pulley with the shaft 23, or to disconnect the pulley from the shaft 55 so that the shaft may be driven to effect intermittently the successive cycles of operations of the machine. Power, however, may be applied to the machine, to run the machine in any other suitable manner. 60 The operation of my invention is as follows:—The magazine 100 being supplied with eyelets, power is applied to the pulley 120 and the shaft 23 and cam disks 22 and 66 are rotated; the feed bar 80 is drawn rearwardly by cam 95 through cam arm 96 and 65 the connections between the bar and lever, until the feed bar recess 81 registers with the lower extremity of the chute 101 to receive an eyelet, during which movement of the feed bar the dog 82 engages the dog 116 and is swung away from said recess as shown in Fig. 4 of the drawings, and the lug 91 on the engaging member 85 engages the cam 90 and raises the engaging member out of its engaging position, as shown in Figs. 7 to 10 inclusive; the brush 110 is oscillated by cam 21 through cam lever 25, link 108, arm 107 and shaft 103, whereby the eyelets in the magazine are swept by the brush into the chute; the eyelets drop down the chute one upon another, the foremost eyelet dropping out of the lowermost end of the chute into the recess 81 in the feed bar 80; the feed bar is then pushed forward by the cam 95 through cam arm 96 and link 98 until the eyelet rests in the path of movement of the punch 14 and set 15, during which movement of the feed bar the dog 82 disengages the dog 116 and engages the eyelet in the feed bar recess 81 and maintains the eyelet in said recess, the lug 91 on the engaging member 85 disengages the cam 90 and said member also engages the eyelet, insuring registration with the punch 14 and set 15 and the side of the feed bar adjacent the chute closes the lower end of the chute and prevents the eyelets dropping out of said end of the chute. When the feed bar is in its forward position and the eyelet is in the path of movement of the punch 14 and set 15 and registers properly therewith, the punch and set are in an elevated position above the eyelet, the anvil 60 is in its rearward position away from the die 7 and the lifting arm 72 is in its lower position. When the feed bar, eyelet, punch, set, anvil and lifting arm are in the above described positions the material in which the eyelet is to be set, is placed upon the die 7 and lifting arm 72; the punch 14 is then forced downward, by the cam 21 through cam lever 25, link 29, stud 28 and punch plunger 16, through the opening in the eyelet and impales the eyelet upon itself; the feed bar 80 is then moved backward by its operating means into its eyelet receiving position and the eyelet being impaled upon the punch causes the dog 82 to swing on its pivot and release the eyelet from the feed bar; as the downward movement of the punch continues the punch punches a hole in the material and ejects the punched out piece of material through the opening 8 and passage 9 in the die 7 and die holder 5 respectively; the punch is then moved upward by its operating mechanism, and the lifting arm 72 is elevated, by means of cam 76 and cam arm 73 which movement of the lifting arm elevates the material a sufficient distance to retain the punch in the opening 125 130

which it has punched in the material and to allow the anvil 60 to pass thereunder; the anvil 60 is then moved forward by cam 65 through cam arm 67 and link 69, over the die 7 until the anvil opening 62 registers with the die opening 8; the lifting arm 72 is then lowered level with the anvil and the punch 14 forced downward through the openings 62 and 8 in the anvil 60 and die 7 respectively during which movements of the lifting arm and punch the material is lowered upon the anvil 60; the set 15 is then forced downward, by cam 40 through cam lever 41, link 42, union 43 and set plunger 17, during which movement the set engages the eyelet and forces the shank thereof through the hole in the material, stripping the material from the punch and transferring the material from the punch to the eyelet; the punch 14 and set 15 and the lifting arm 72 are then raised, by their respective operating cams, and the material and eyelet are raised by said lifting arm, into such positions that the punch and eyelet will be entirely out of the anvil opening 62 and with the eyelet still impaled on the punch; the anvil is then moved forward by its operating cam until the die 63 rests directly in the path of movement of the punch and set and registers with the shank of the eyelet; the punch is then moved downward until its lower end rests centrally upon the die 63, to insure accurate registration of the eyelet with the die when the eyelet descends upon the die; the lifting arm 72 is then lowered level with the anvil and the set is forced downward against the head of the eyelet, and the shank of the eyelet is thereby driven against the die 63 and clenched by the die against the under side of the material, thus setting the eyelet in the material. The punch and set are then withdrawn from the eyelet and the material, the punch being withdrawn in advance of the set to strip the eyelet and material from itself and the material with the eyelet set therein is removed.

The lifting arm 72, while it affords a positive means for lifting the material, after it is punched, over the anvil 60 is not an indispensable means for accomplishing this operation, under ordinary conditions, inasmuch as the material, under such conditions, adheres to the punch after it punches the material and is lifted by the punch. However, the material is liable to slip on the punch and fail to be elevated above the anvil by the punch especially if the material is heavy, in which event the machine would have to be stopped and the material adjusted by hand, thus impairing the efficiency of the machine, were it not for the lifting arm which insures the lifting of the material.

In case an eyelet should fail properly to

enter the recess 81 of the feed bar 80, said eyelet will be engaged by the feed bar and forced against the dog 116, upon the forward movement of said dog which will cause said dog to swing forwardly on its pivot out of alinement with the forward side wall of the chute passageway, and permit the eyelet to escape, thus avoiding choking of the chute and interference with the operation of the eyelet feed bar.

I do not limit myself to the exact construction and arrangement of the parts of my invention herein shown and described. Variations and modifications may be made without departing from the spirit of the invention.

I claim:

1. A punching and eyeleting machine comprising a support for the material, a punch adapted to punch a hole in the material with the material resting on said support, an anvil located above said support, means for elevating the material above said support after the material is punched, means for moving said anvil under said material in its elevated position, and a set adapted to coöperate with said anvil to set the eyelet in the material within said hole.

2. A punching and eyeleting machine comprising a support for the material, a punch adapted to punch a hole in the material with the material resting on said support, an anvil located above said support, means for elevating the material, after it is punched, above said support, means for positively moving said anvil under said material in its elevated position, and a set adapted to coöperate with said anvil to set the eyelet in the material within said hole.

3. A punching and eyeleting machine comprising a support for the material, a punch adapted to punch a hole in the material, means for delivering the eyelet to the punch to be impaled thereon, an anvil located above the support, means to enable the material to be placed upon said anvil, a set, said anvil provided with a hole, adapted to co-act with said punch and set for inserting the eyelet in said hole in the material, and a set co-acting part adapted to co-act with said set for setting the eyelet in the material.

4. In a machine of the character described, a support for the material, a punch for punching a hole in the material, an anvil adapted to rest above the support, a lifting arm for lifting the material, after it is punched, to enable the material to be placed upon said anvil, a cam for operating said lifting arm, and a set adapted to co-act with said anvil to set the eyelet in the material within said hole.

5. In a punching and eyeleting machine, in combination with an anvil, a set, a support for said set, said support provided with

an inclined seat, said set provided with an inclined flange and a thread, a nut adapted to fit said thread and to engage said support to draw said flange against said seat to center the set and maintain it in position on said support, and means for actuating said set to co-act with said anvil to set the eyelet in the material.

6. A punching and eyeleting machine, comprising a punch and die, a set in axial alignment with said punch, and an anvil provided with a hole and a set co-acting part, and means automatically for moving said anvil to bring said hole and set co-acting part respectively into alignment with said punch and set for inserting and setting the eyelet into the material.

7. A punching and eyeleting machine comprising a punch and die for punching a hole in the material, a set, an anvil provided with a hole, adapted to co-act with said punch and set to receive the punch and shank of the eyelet for inserting the shank of the eyelet through the hole in the material, and a set co-acting part adapted to co-act with the set to set the eyelet into the material.

8. A punching and eyeleting machine comprising a punch and die permanently in alignment with each other, a set, an anvil provided with a hole and a set co-acting part, and means for moving the anvil to bring said hole and co-acting part respectively into co-acting position with said set for inserting and for setting the eyelet in the material.

9. A punching and eyeleting machine comprising a punch and die permanently in alignment with each other, a set, an anvil provided with a hole, and a punch and set co-acting part, and means for moving the anvil to bring said hole and co-acting part respectively into co-acting position with said punch and set for inserting and for setting the eyelet in the material.

10. In a machine of the character described a support for the material, a punch for punching a hole in the material, an anvil adapted to rest above the support, means for lifting the material after it is punched, to enable the material to be placed upon said anvil, and a set adapted to co-act with said anvil to set the eyelet in the material within said hole.

11. In a punching and eyeleting machine, a punch and die adapted to punch a hole in material, a tubular set in axial alignment to said punch and an anvil provided with an eyelet shank receiving means and an eyelet setting part adapted to co-act with

said punch and set, means for intermittently reciprocating said punch to impale an eyelet, to punch a hole in the material, to guide said eyelet into the material and to maintain said eyelet in position while being clenched in the material, means for intermittently reciprocating said tubular set to co-act with the eyelet receiving means, and to co-act with the eyelet setting part of said anvil, and means for reciprocating said anvil to co-act with said punch and set for introducing and setting the eyelet into the material.

12. In a punching and eyeleting machine, a punch and die for punching a hole in the material, means for intermittently reciprocating said punch to impale an eyelet thereon, to punch a hole in the material in advance of the eyelet, to guide the eyelet into the hole punched in the material and to maintain the eyelet in position while being clenched in the material, a set and an anvil, said set adapted to force the eyelet along the punch into the hole in the material and thereby strip the material from the punch, said set and anvil adapted to co-act with each other to set the eyelet in the material.

13. A punching and eyeleting machine comprising a punch, a die, and a set arranged permanently to be in axial alignment, said set adapted to slide independently on said punch and set an eyelet, means for intermittently reciprocating said punch to punch a hole in the material and to guide an eyelet therein and an anvil adapted to be moved between said punch and set and said die into co-acting relation with said punch and set, to insert and set an eyelet into the material.

14. A punching and eyeleting machine comprising a punch, a die, and a set arranged permanently to be in axial alignment, said set adapted to slide independently on said punch and set an eyelet, said punch adapted to impale an eyelet, to punch a hole in the material, and operate to guide said eyelet therein and an anvil adapted to be moved between said punch and set and said die into co-acting relation with said punch and set to set an eyelet in the material.

In testimony whereof I have signed my name to this specification in the presence of two subscribing witnesses.

HENRY C. HINCHCLIFF.
